UNITED STATES PATENT OFFICE.

EDWARD HENRY LESCURE, OF HARRISBURG, PENNSYLVANIA, ASSIGNOR TO THE PENNSYLVANIA STEEL COMPANY, OF PHILADELPHIA, PENNSYLVANIA, A CORPORATION OF PENNSYLVANIA.

BUR-REMOVER.

963,596.

Specification of Letters Patent.

Patented July 5, 1910.

Application filed June 18, 1909. Serial No. 502,932.

To all whom it may concern:

Be it known that I, EDWARD HENRY LESCURE, a citizen of the United States of America, residing at Harrisburg, county of 5 Dauphin, State of Pennsylvania, United States of America, have invented certain new and useful Improvements in Bur-Removers; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

My invention relates to bur removers for removing the burs formed in punching or otherwise making holes in iron and steel, especially in structural iron and steel, and 20 has for its object to provide a simple and efficient device for rapidly removing the burs either from a single plate or from a number of assembled plates, and comprises a driven spindle carrying bur removing elements or cutters adapted to act on opposite surfaces with a planing or scraping action, together with details of construction 25 hereinafter to be more fully described and claimed.

30 Referring to the drawings, in which like parts are similarly designated: Figure 1 is a longitudinal section partly in elevation. Fig. 2 is a side elevation of the spindle with one of the knife carrying elements in section. Fig. 3 is an elevation of a rod for actuating the pivoted cutters. Fig. 4 is a perspective view of the pin. Fig. 5 is a longitudinal sectional view of a modification with parts shown in elevation. Fig. 6 35 is an elevation of the parts shown in section in Fig. 5. Fig. 7 is an elevation at right angles to Figs. 5 and 6.

The mechanism is preferably driven by an electric, pneumatic, or other suitable form 40 of motor capable of rotating a shaft 3 having a threaded end and mounted in the casing 2, Fig. 5, the details of structure of which motor form no part of the present invention. The casing 2 is provided with 45 alined handles 4 secured in diametrically oppositely situated bosses 5 on the casing 2 as shown in Fig. 5.

Detachably secured to the rotary shaft 3

by an internal thread or otherwise, is a spindle 6 which carries and drives the bur 55 removing elements. Said spindle is provided with a longitudinal central bore 7 in which is vertically movable a rod 8. Passing transversely through the spindle 6 and intersecting the central bore 7 is a long slot 60 9. Surrounding the spindle is an operating sleeve 10 the exterior of which is roughened or knurled for hand gripping. This sleeve is connected to the rod 8 by means of a pin 11, more clearly shown in Fig. 4 that passes 65 through the rod 8 so that the ends of the pin project into an internal recess in the sleeve 10 over a shoulder 12, the recess being closed by a nut 13 to retain the pin in the recess, and thus afford a means of vertically 70 moving rod 8 during rotation, by the manipulation of the sleeve. The rod 8 near its lower end is provided with racks 14 symmetrically disposed on its periphery. In the lower end of the spindle is a short slot 15 75 and in this slot are pivoted by pivots 16 cutters or knife blades 17 having at one end toothed sectors 18 concentric with the pivots, while the other ends of the blades are extended to form cutters which at one time 80 may extend outside the spindle, with the backs thereof resting against the lower end of the slot 15, the upper edges of the knives being sharp and arranged for cutting on the underside of the plates. The toothed or 85 sector portion of the lower knives engages the racks 14 on opposite sides of the lower end of the rod 8, so that a downward movement of rod 8 will swing the knives on their pivots and withdraw their cutting extensions entirely within the spindle 6. Rod 8 at its upper end is provided with a head 19 fitting into the longer portion of the bore 7 in the spindle 6 and between the head and the base of the longer portion of the bore 7 is a coil 90 spring 21 to hold the rod 8 normally in the position shown in Fig. 1. The rod 8 is provided with a number of perforations 22 for the reception of pin 11 to enable the device to be adjusted for different thicknesses of 100 plates. Below the shoulder 12 the bore of the sleeve 10 is enlarged to provide for mounting therein a cutter sleeve 23 slidably fitted on the spindle 6 and provided with an interior recess 24 in which is seated a coil 105 spring 25 surrounding the spindle 6 and

whose upper end engages the actuating sleeve 10 under the shoulder 12. The cutter sleeve 23 is provided near the middle with an exterior shoulder 26 and at its lower 5 end is enlarged by a flange 27. The lower end of the actuating sleeve 10 is provided with one or more countersunk screws 28 to hold the cutter sleeve 23 in slidable relation to the actuating sleeve 10.

- 10 The cutter sleeve 23 carries an upper cutter or cutters here shown as two cutters 29 the shanks of which rest in internal grooves in sleeve 23, the enlargement on the upper ends of the cutters 29 entering an internal 15 annular groove 30 in the sleeve 23, the enlarged lower ends of the cutters extending under the lower end of the sleeve 23 having preferably beveled cutting faces which are pressed against the plates being burred.
- 20 The backs of these cutters are slidably seated in longitudinal grooves 31 in the spindle 6, by which the cutters are carried around, by rotation of the spindle 6 with the cutter carrying sleeve 23, the application of the 25 cutters to the upper surface of the plates being controlled by the sleeve 10 in conjunction with cutter-carrying sleeve 23.

In the modification of my bur remover shown in Figs. 5, 6 and 7 in which 6^a is the spindle having an internally threaded end for connecting it to the shaft 3 of the motor, there is provided a slot 9^a in the spindle considerably shorter than the slot 9 of Fig. 1, and I preferably make the sleeve 10^a considerably longer than in Fig. 1 and arrange to have it completely cover slot 9^a. The ends of the pin 11^a used for coupling the rod 8^a in bore 7^a to the sleeve 10^a project into an internal annular groove 9^c in the 30 sleeve 10^a using screw plugs 10^b to keep the pin 11^a from working out of rod 8^a. In Fig. 5 I have shown a number of holes through rod 8^a, whereby the portion of the actuating sleeve 10^a may be adjusted relatively to the rod 8^a by inserting the pin 11^a 35 in any one of them.

In the spindle 6^a I provide near its lower end a pair of pivoted cutters or knives 17^a arranged for cutting on the underside of 40 plates, and arranged for being withdrawn into the spindle by downward movement of rod 8^a with racks 14^a that engage the toothed sectors 18^a of the blades 17^a pivoted at 16^a in slot 15^a as shown in Fig. 5. For removing burs on the upper surfaces of plates I also provide an additional slot 15^b in which 45 are pivoted at 16^b cutters or blades 17^b provided with toothed sectors 18^b that engage with another set of racks 14^b formed on rod 8^a, as shown in Fig. 5, the backs of the cutters 17^b being uppermost and arranged to 50 rest against the upper end of the slot 15^b when the cutting extensions are thrust out for cutting, at which time the cutting edges

of the cutters 17^b are in position for acting 65 on the upper surface of the plates, the cutters 17^b being thrown into that position by downward movement of the rod 8^a.

The operation of my device is as follows: The spindle 6 being driven by the motor, carries with it the pivoted cutters 17, also the cutters 29. The actuating sleeve 10 is free to be held stationary by the hand of the operator, by reason of the pin 11 rotating in the annular groove formed between the shoulder 12 and the nut 13. By gripping the actuating sleeve 10 and pulling it downward to a small extent the cutters 17 are positively moved or rotated on their pivots 16 and placed in position within the spindle 70 for passing into the drilled or punched hole, until the cutters 29 on the cutter-sleeve 23 engage the upper surface of the plate and remove the bur. Then by raising the actuating sleeve 10 the pressure transmitted 75 through the spring 25 to the cutter sleeve 23 is relieved and the rod 8 is moved upward 80 to throw the cutters 17 into the position shown in Fig. 1. The entire tool is then raised until the edges of the cutters 17 come 85 into contact with the lower surface of the plate to remove the bur thereon. The entire tool and then the actuating sleeve 10 is moved downward to move the rod 8 again 90 against its spring 21 to turn the pivoted cutter 17 within the slot 15, after which the tool is lifted out of the hole, and the operation is repeated with respect to other holes 95 from which burs are to be removed. It will be noted that both the upper cutter or cutters 29 and the lower cutter or cutters 17 are 100 revolved by the spindle.

To change the adjustment of the upper cutters, to use the device on different thicknesses of single or assembled plates removal 105 of the nut 13 enables the pin 11 to be shifted to the desired opening 22 in rod 8, where it will be retained by replacing the nut.

The operation of the modification is similar to that just described with the exception 110 that the upper and lower cutter sets are alternately withdrawn into and projected from the spindle by the movement of sleeve 10^a.

I claim:

1. In a bur remover, the combination with a hollow spindle having longitudinal grooves therein and capable of being rotatively driven; of a rod longitudinally movable in the spindle and having a plurality of holes 120 transversely therethrough, a cutter sleeve mounted on the spindle and having cutter seats therein registering with said grooves, cutters in said seats and grooves, to non-rotatably and slidably secure the sleeve and spindle together, an actuating sleeve, a pin passing through one of the holes in said 125 rod and secured in the actuating sleeve, a

- spring between the two sleeves surrounding the spindle and pivoted cutters mounted in the spindle and actuated by the rod.
2. In a bur remover, the combination with 5 a hollow spindle capable of being rotatively driven and having upper and lower slots; of a rod having a head thereon and longitudinally movable in the spindle, a spring acting on said head to retract the rod, a cutter 10 sleeve on the spindle having a shoulder 26, an actuating sleeve surrounding the cutter sleeve, a pin passing through the upper slot and the rod and rotatably held in the actuating sleeve, a spring between the two sleeves, 15 a screw in the actuating sleeve in the path of movement of the cutter sleeve, cutters mounted between the cutter sleeve and spindle, and pivoted cutters in the lower slots actuated by the rod.
- 20 3. In a bur remover, the combination with a hollow spindle capable of being rotatably driven and having a slot in its lower end; of a rod having longitudinal movement within the spindle, an operating sleeve for 25 said rod, racks on the rod and cutters pivoted in the slot in the spindle and having toothed sectors thereon engaged by said racks.
4. In a bur remover the combination with 30 a hollow spindle capable of being rotatively driven and having a slot near its lower end and a slot above the first mentioned slot; of cutters pivoted in the lower slot, a rod longitudinally movable in the spindle and 35 having racks thereon to engage the cutters to positively project them from and withdraw them into the slot and spindle and means operating in the upper slot to move said rod.
- 40 5. In a bur-remover the combination with a spindle and means to rotatively drive the same; of upper and lower cutters both mounted to rotate in unison with the spindle and driven thereby and means to adjust the 45 upper cutters to vary their distance from the lower cutters.
6. In a bur-remover the combination with a spindle and means to rotatively drive the same; of a cutter sleeve slidably mounted on the spindle and cutters in operative relation to the spindle and sleeve. 50
7. In a bur remover the combination with a spindle having lateral grooves therein; of a cutter sleeve loose thereon having internal grooves registering with those in the spindle 55 and cutters whose shanks take into the registering grooves.
8. In a bur-remover the combination with a spindle having lateral grooves and means to rotatively drive the spindle; of a cutter 60 sleeve having internal grooves registering with those in the spindle, cutters whose shanks take into the registering grooves, an operating sleeve loose on the cutter sleeve and means to connect the sleeves to permit 65 the cutter sleeve and spindle to rotate independently of the operating sleeve.
9. In a bur-remover the combination with a hollow spindle, a rod longitudinally movable in the spindle and pivoted cutters actuated by the rod; of a cutter sleeve slidable 70 but not revoluble with respect to spindle and an operating sleeve connected to the rod and to the cutter sleeve to permit rotation of the rod, spindle and cutter sleeve independently 75 of the operating sleeve.
10. In a bur-remover the combination with a hollow spindle, a rod longitudinally movable in the spindle, and pivoted cutters actuated by the rod; of a cutter sleeve slidable 80 but not rotatable with respect to the spindle, an operating sleeve in rotatable connection with the cutter sleeve and means to connect the operating sleeve and rod to permit the adjustment of said sleeve longitudinally of 85 the rod and thereby adjust the distance between the pivoted cutters and cutter sleeve.
- In testimony that I claim the foregoing as my invention, I have signed my name in presence of two subscribing witnesses.
